UNITED STATES PATENT OFFICE

92,879

DESIGN FOR A SEAL FASTENER FOR SHEET MATERIAL

Morris Canter, New York, N. Y.

Application May 3, 1934, Serial No. 51,664

Term of patent 14 years

To all whom it may concern:

Be it known that I, MORRIS CANTER, a citizen of the United States, residing in New York, county and State of New York, have invented a new, original, and ornamental Design for a Seal Fastener for Sheet Material, of which the following is a specification, reference being had to the accompanying drawing, forming part thereof.

Fig. 1 is a perspective view of a seal fastener for sheet material showing my new design; and

Fig. 2 is a plan view of the same.

I claim:

The ornamental design for a seal fastener for sheet material, as shown.

MORRIS CANTER.
